UNITED STATES PATENT OFFICE.

WILLIAM G. ENTREKIN, OF PHILADELPHIA, PENNSYLVANIA.

PHOTOGRAPHIC-PRINT WASHER.

SPECIFICATION forming part of Letters Patent No. 353,849, dated December 7, 1886.

Application filed May 14, 1886. Serial No. 202,159. (No model.)

To all whom it may concern:

Be it known that I, WILLIAM G. ENTREKIN, a citizen of the United States, residing in Philadelphia, Pennsylvania, have invented 5 certain Improvements in Photographic-Print Washers, of which the following is a specification.

The main object of my invention is to so construct a photographic-print washer as to 10 effect the elimination of the soda from the print in a short time, so that the brilliancy of the albumen surface will not be dulled as it is by long-continued washing, further objects of the invention being to prevent the 15 overflow of the pan, to insure the continual movement of the prints while they are being washed, and to prevent the clogging of the perforations in the lower jet-pipe of the pan.

In the accompanying drawings, Figure 1 is 20 a perspective view of a photographic print washer constructed in accordance with my invention; Fig. 2, a transverse section of the same; and Fig. 3, a sectional plan on the line 1 2, Fig. 2.

25 A is the casing of the pan, which has an inverted conical bottom, a, communicating with the drain-pipe B, with which also communicates an overflow-pipe, D, and a siphon-pipe, F, the drain-pipe being provided with a valve 30 or cock, b, and the siphon-pipe with a similar valve or cock, f, but the overflow-pipe providing at all times a free outlet from the pan.

Within the pan is a print cage, G, having 35 perforated bottom and sides, and around the bottom of this cage are arranged two semi-circular pipes, H H', each of these pipes communicating near one end with a branch, h, of a water-supply pipe, I, and near the opposite end with a branch, h', of a drain-pipe, J.

40 In the pipes H H' are formed inclined perforations, so that the water escapes therefrom in the form of a number of inclined jets, which impinge upon the prints, wash the same, and at the same time cause the continued rotary 45 motion of the mass of prints in the cage, this washing and turning movement being supplemented by similar inclined jets escaping from orifices in an annular pipe, K, arranged around the top of the cage and communicating through 50 a branch, k, with a branch, I', of the water-supply pipe I. This branch I' terminates in

a rose or sprinkler, M, located centrally above the cage, and serving to direct a number of jets in the form of a shower upon the prints contained in said cage.

55 All of the supply-branches h, h, k, and I', and the discharge-branches h' h' are provided with suitable cocks or valves, whereby the flow through either of said branches can be controlled.

60 When the machine is at work, the valves are adjusted as shown in the drawings, all the valves in the supply-branches being opened, and all the valves in the discharge-branches being closed, so that the waste water over 65 flows through the pipe D.

The print-cage G is less in diameter than the pan A, so that an annular chamber, x, is 70 formed around the cage, from which chamber the overflow takes place, and as the prints cannot escape from the internal cage there can be no obstruction of the overflow by reason of a print being drawn into or over the mouth of the same, as in that class of washers in which the overflow takes place directly from the cage 75 or pan in which the prints are placed.

When it is desired to effect the automatic draining of the pan at intervals, the valve in the siphon-pipe F may be opened, and either of the pipes H H' may be utilized as a drain-pipe, if desired, by closing the valve in the supply branch and opening the valve in the discharge-branch communicating with said pipe, the flow of water inward through the 80 perforations serving to dislodge therefrom any 85 obstructions which may have been lodged therein by the outward flow of water.

Owing to the constant agitation of the prints and to the numerous jets of water, both from above and below, to which they are subjected, 90 and owing, also, to the ready escape of the waste water from all parts of the sides and bottom of the print-cage, the prints can be thoroughly washed in a very short time, so that there is no loss of brilliancy in the albumen surface, such as is caused by long-continued washing. Moreover, all parts of the pan are made of sheet metal, and there is, hence, no tendency to absorb and retain the soda, as in the case of washing pans or trays made 95 wholly or in part of wood.

The soda washed from the prints collects in

the chamber beneath the perforated bottom of the print-cage, and is drawn off from said chamber by the siphon-pipe, so that there can be no accumulation of soda solution in the lower part of the print-cage, as in apparatus in which the inlet of the siphon-pipe is above the bottom of said cage.

I claim as my invention—

1. The combination of the pan having a print-cage and a chamber beneath the same, with the siphon-pipe communicating with said chamber beneath the cage, all substantially as specified.

2. The combination of the print-cage with a perforated pipe located in the lower portion of the same, and having a valved supply-pipe and a valved discharge-pipe, whereby either an inward or an outward flow of water through said pipe may be maintained, all substantially as specified.

3. The combination of the print-cage with two pipes located near the bottom of the same, and each having a valved inlet-pipe and a valved discharge-pipe, all substantially as specified.

4. The combination of the print-cage with perforated pipes extending around the same at top and bottom, all substantially as specified.

5. The combination of the pan, drain-pipe, an unobstructed overflow-pipe, and a siphon drain-pipe, all substantially as specified.

In testimony whereof I have signed my name to this specification in the presence of two subscribing witnesses.

W. G. ENTREKIN.
